(21) Appl. No.: **29/299,087**

(57) **CLAIM**

(22) Filed: **Dec. 19, 2007**

The ornamental design for a combined speaker and amplifier,
as shown.

(30) **Foreign Application Priority Data**

Jul. 20, 2007 (JP) 2007-019736

DESCRIPTION

(51) **LOC (8) Cl.** **14-01**

FIG. 1 is a perspective view of the top, front and right side of
a combined speaker and amplifier showing our new design;

(52) **U.S. Cl.** **D14/172; D14/168**

FIG. 2 is a top plan view thereof;

(58) **Field of Classification Search** D14/204,

FIG. 3 is a front elevational view thereof;

D14/209–216, 136, 168, 172, 496, 188, 194,
D14/197; 181/143–144, 147–148, 150, 157,
181/198–199, 151, 153; 381/300–302, 306,
381/333, 345, 361–364, 386–388, 332, 336

FIG. 4 is a right side elevational view thereof;

See application file for complete search history.

FIG. 5 is a left side elevational view thereof;

FIG. 6 is a bottom plan view thereof; and,

FIG. 7 is a rear elevational view thereof.
